FIG. 1.

FIG. 2.

Des. 194,261

PAGE 2

FIG. 3.

FIG. 4.**FIG. 6.****FIG. 5.**FIG. 1 is a front elevational view of an illuminable wall bracket for railings or the like embodying my new design;

FIG. 2 is a side elevational view thereof;

FIG. 3 is a front perspective view thereof;

FIG. 4 is a front elevational view of a modified form of FIG. 1;

FIG. 5 is a top plan view thereof as shown in FIG. 5; and

FIG. 6 is a side elevational view thereof as shown in FIG. 4.

The dominant features of my design reside in the portions shown in full lines. The fragmentary railing and supporting element are disclosed for illustrative purposes only.

The inner flat surface of the bracket as shown in FIGS. 1, 3, and 4 is foraminous as indicated by the openings shown in dotted lines.

This is a continuation application of my copending applications Serial No. D. 63,156, filed December 8, 1960, and Serial No. D 63,157, filed December 8, 1960, and now abandoned.

I claim:

The ornamental design for an illuminable wall bracket for railings or the like, as shown and described.
